UNITED STATES PATENT OFFICE.

HENRY SCHUETZ, OF PITTSBURGH, PENNSYLVANIA.

COMBINATION TOOL.

Application filed June 18, 1920. Serial No. 389,888.

To all whom it may concern:

Be it known that I, HENRY SCHUETZ, a citizen of the United States and a resident of Pittsburgh, Allegheny County, and State of Pennsylvania, have invented certain new and useful Improvements in Combination Tools, of which the following is a specification.

My invention relates to combination tools, and a purpose of my invention is the provision of a combination tool which is adaptable to a plurality of uses, and which is of simple and efficient construction, it being capable of being placed in compact form when not in use.

I will describe one form of combination tool embodying my invention and will then point out the novel features thereof in claims.

20 In the accompanying drawings:

Figure 1 is a view showing in side elevation the main body of the tool which constitutes a carpenter's square.

25 Fig. 2 is a longitudinal sectional view taken on the line 2—2 of Fig. 1.

Fig. 3 is a view showing in end elevation a square shown in Fig. 1.

30 Fig. 4 is a transverse section taken on the line 4—4 of Fig. 1.

35 Fig. 5 is a view showing in side elevation a rule adapted to be used in conjunction with the square shown in Fig. 1.

Fig. 6 is a view showing in side elevation a tool holder adapted to be used in conjunction with the square shown in Fig. 1.

40 Fig. 7 is a view showing in end elevation the tool holder shown in Fig. 6.

Fig. 8 is a view similar to Fig. 7 showing the opposite end of the tool holder.

45 Fig. 9 is an assembled view of the square and rule, the former being in folded position and showing in phantom the tool holder in applied position.

Fig. 10 is a detailed view of a screw-driver adapted to be supported by the tool holder shown in Fig. 6.

50 Fig. 11 is an assembled view of the square and rule to which are applied a pair of jaws constituting a caliper.

Fig. 12 is a perspective view of one of the jaws shown in Fig. 11.

55 Fig. 13 is a fragmentary detailed perspective view of one end of the rule shown in Fig. 5.

Fig. 14 is a view showing in side elevation the square and rule shown in Fig. 1 and having applied thereto a spur and a bracket, the latter supporting a pencil and thus converting the tool into a divider.

Fig. 15 is a detailed perspective view of the spur shown in Fig. 14.

Fig. 16 is a detailed perspective view of the bracket shown in Fig. 14.

Fig. 17 is a fragmentary view showing in side elevation the square and rule employed as a razor blade holder.

Fig. 18 is a view similar to Fig. 17 showing another form of razor blade in applied position.

Similar reference characters refer to similar parts in each of the several views.

Referring specifically to the drawings and particularly to Figs. 1 to 4 inclusive, S designates generally a carpenter's square comprising a main arm s' carrying at one of its ends a relatively short arm s² which is pivotally supported thereon by means of a pivot pin 16 extending through a block 17, as clearly shown in Fig. 2. As shown in Fig. 3, the arm s' is C-shaped in cross-section to provide inwardly extending flanges 18. Arranged within the arm s' and beneath the flanges 18 is a longitudinally extending leaf spring 19 which as shown in Fig. 2 is bowed longitudinally with one end formed with a lip 19^a secured within a recess 17^a of the block 17, while its opposite end normally bears against the bottom of the arm. The arm s² is U-shaped in cross-section so that it can be folded into compact position upon the arm s' in the manner shown in Fig. 9. Both of the arms s' and s² are provided with graduations, as clearly shown in Fig. 14.

Referring now to Fig. 5, I have here shown a carpenter's rule designated generally at R and comprising a main section r' and a relatively narrow section r² both of which are provided with graduations so that in extended position, the graduations of one section are a continuation of the graduations of the other section. The section r² is pivotally connected to the section r' as indicated at 20, and by virtue of this connection, either section can be folded so as to lie beside the other section or extended so as to lie end to end as shown in phantom in Fig. 5. As shown in Figs. 5 and 13, the free end of the section r' is provided with a T-shaped head

21 which is adapted to be used in supporting certain tools as will be hereinafter described.

As shown in Fig. 11, the sections r' and r^2 can be slid into the main arm s' of the square S, the section r^2 when in folded position being disposed between the flanges 18, so that when the rule is pushed home within the arm s' , it will be compactly housed 10 therein with the exception of the head 21 which projects beyond the end of the arm as shown in Fig. 14. The rule is frictionally held within the arm s' by means of the spring 19, it being understood that the spring is so 15 bowed as to be held under tension when the rule is within the arm and to thus force the latter into engagement with the flanges 18. A locking of the rule within the square can be effected by folding the arm s^2 onto the 20 arm s' in the manner shown in Fig. 9 so as to engage an outstruck projection 22 formed on the section r^2 as shown in Figs. 9 and 11.

Referring now to Figs. 6, 7 and 8, I have here shown a tool holder designated generally at T and comprising a slotted body 23 having an ovate cross-sectional contour as shown in Fig. 7, with one end thereof provided with a head 24. The head 24, as shown in Fig. 8, is formed with a socket 24^a which is adapted to receive a correspondingly shaped head 25 formed on a tool designated generally at L. As shown in Fig. 9, the tool L in the present instance includes the head 25 which is preferably 35 tapered in length so as to wedge within the socket 24^a to securely hold the tool upon the tool holder. The tool L also includes a shank 26, and between the shank 26 and the head 25 is a nurled projection 27 which 40 is adapted to be gripped in effecting the application or removal of the tool to or from the tool holder. The shank 26 in the present instance is provided with a glass cutting implement 28, while in Fig. 10 it is 45 formed with a screw-driver, designated at 29. It will be understood that either of the tools shown in Figs. 9 and 10 can be inserted into the socket 24^a of the tool holder. The tool holder itself is adapted to be supported 50 upon the arm s' of the square S in the manner shown in dash lines in Fig. 9, it being understood that the inner contour of the body 23 corresponds to the cross-sectional contour of the arm s' so that it can be readily 55 inserted thereon and frictionally held against accidental displacement.

Referring now to Fig. 11, I have here shown a pair of jaws J and J' which are associated with the square and rule, respectively, to provide a pair of calipers. As shown in Fig. 12, the jaw J comprises a head 30 which is slotted longitudinally as indicated at 30^a to receive the T-shaped head 21 and the adjacent portion of the rule section 65 r' . The head 30 is provided with an ex-

tension constituting an arm 31 which is adapted to cooperate with a similar arm 31^a formed on a head 32 of the jaw J' in a manner to form a pair of calipers, as will be understood. The head 32 of the jaw J' slidably fits upon the arm s' of the square S in the manner shown in Fig. 11 and is adapted to be locked on the end of such arm by means of a set-screw 33. The jaw J is locked against accidental displacement 70 from the head 21 by means of a similar set-screw 34. As the rule R is slidably fitted within the square S, it will be clear that by adjusting the rule longitudinally within the arm s' , the position of the jaw J with respect to the jaw J' can be correspondingly varied to suit the particular work to which the calipers are adapted to be applied. As shown in Fig. 11, the outer edges of the arms 31 and 31^a are of angular formation 85 to permit of the measuring of the internal diameters of pipes and the like.

Referring now to Figs. 14, 15 and 16, I have here shown the head 21 carrying a spur 35 which as shown in Fig. 15 comprises two 90 tapered strips of metal secured together intermediate their ends by means of a pin 36. The wide ends of the strips are bent outwardly and inwardly in opposite directions to provide clamping jaws 37 which are 95 adapted to embrace the head 21 for securely retaining the spur as a unit upon the rule. The arm s^2 of the square S carries a bracket designated generally at B. This bracket as shown in Fig. 16 comprises a pair of resilient 100 jaws 38 shaped to embrace the arm s^2 in a manner to prevent accidental displacement of the bracket from the arm. The bracket also includes a clamp 39 which is adapted 105 to receive and frictionally retain a conventional form of pencil or other marking tool designated at P upon the bracket and in proper position upon the arm s^2 so that when the arms s' and s^2 are in folded position, as shown in Fig. 14, the pencil and spur cooperate to provide a divider.

Referring now to Fig. 17, I have here shown the square S and the rule R employed as a razor blade holder. As shown in Figs. 1 and 17, the arm s' is slotted at one edge as indicated at 40, such slot effecting a communication with the interior of the arm and being of such a length as to accommodate a safety-razor blade of the standard construction. In Fig. 17, I have shown a Gillette 120 razor blade indicated at 41 in applied position within the arm s' . In this position, the blade 41 is disposed below the flanges 18 and is engaged by the spring 19 thus frictionally retaining the blade within the arm. To lock the blade against accidental displacement from the arm, the rule R is moved to its innermost position so that it overlies a portion of the blade 41 and thus 125 securely clamps the blade between the rule 130

and the spring 19. After the rule has been moved to this position the arm s^2 is moved to folded position, thus engaging the lug 22 to prevent the withdrawal of the rule from the arm.

In Fig. 18, I have shown the tool employed as a holder for razor blades of the Gem type, such blade being indicated at 42 and in its applied position having the reinforced edge thereof disposed between the flanges 18 so that when the arm s^2 is moved to folded position, the blade as a whole will be securely clamped within the tool against lateral displacement. To prevent longitudinal displacement of the blade, the rule R is moved so that its inner end abuts the adjacent end of the blade 42 in the manner shown in Fig. 18.

It will be understood that the blades held within the tool as described in connection with Figs. 17 and 18, permits of the holding of the blades during honing or stropping. However, in Fig. 18, the tool can function as a razor when a suitable safety device (not shown) is applied to the blade.

Although I have herein shown and described only one form of combination tool embodying my invention, it is to be understood that various changes and modifications may be made herein without departing from the spirit of the invention and the spirit and scope of the appended claims.

What I claim is:

1. In combination, a holder comprising a main arm having a channel, a second arm of U-shape in cross section pivotally connected to the main arm and adapted to embrace the main arm when turned into closed position thereon, a leaf spring within the channel of the main arm; and a rule comprising a main section adapted to slidably fit within the channel of the main arm and adapted to be frictionally held in adjusted position by said spring, and a second section pivotally connected to the main section, each of said sections being provided with graduations, and said second section having means to cooperate with the said second arm of the holder for supplementing the spring and preventing accidental displacement of the rule when the holder is closed.

2. In combination, a holder comprising

folding sections each of which is provided with a channel, a spring within said channel, and a rule comprising folding sections adapted to slidably fit within said channel, one of which rule sections is engaged by said spring for retaining the rule in adjusted position and the other of which rule sections has means to engage with the other section of the holder into the channel of which the first section is movable to supplement the spring and retain the rule within the holder.

3. In combination, a square comprising foldable arms one of which is formed with flanges to provide a channel and the other of which is U-shaped in cross-section and adapted to embrace the channeled arm when in the closed position thereon, a spring within said channel, and a rule comprising foldable sections, one of said sections fitting within said channel and engaged by said spring, and the other section adapted to be disposed between said flanges and having a projection adapted to be engaged by the other arm of said square for securely holding the rule as a unit against displacement from said channel when the said arm is in closed position on said first named arm.

4. A rule holder adapted to form a square when in fully open position, consisting of a channeled arm having a block at one end, a second arm of U-shaped cross-section adapted to embrace the channeled arm when the said second arm is in the closed position thereon and pivotally connected at one end to said block, a spring within the channel of the first arm having one end engaged and held by said pivot block and a rule slidably in the channel of the first arm and frictionally engaged and held by the said spring.

5. A rule holder adapted to form a square when in fully open position, consisting of a channeled arm having a block at one end, a second arm of U-shaped cross-section adapted to embrace the channeled arm when in the closed position thereon and pivotally connected at one end to said block, and a spring within the channel of the first arm, said block having a groove, and said spring having a flange at one end seated in the said groove and held by said block.

HENRY SCHUETZ.
